CLEANER FOR BELT AND LOWER ROLLER
OF ELEVATING GRADERS

Adolph G. Anderson, Spencer, Iowa

Application October 1, 1938, Serial No. 232,897

2 Claims. (Cl. 198—229)

This invention relates to a means for cleaning the belt and lower roller of elevating graders, and it consists in the constructions, arrangements and combinations herein described and claimed.

A common difficulty experienced with elevating graders is that an accumulation of dirt or soil on the inner side of the elevating belt causes the lower roller of the machine to clog and cease to function, making it necessary in many instances to stop the operation, in order that the foreign matter may be removed.

It is therefore the object of the invention to provide a scraper device which may be readily installed upon the carrier sills of the grader, being adjustably related to the lower roller.

It is also an object of the invention to provide the scraper device with a plurality of deflecting vanes for effecting discharge of loosened material, to the sides of the elevator.

Additional objects, advantages and features of invention will be apparent from the following description, considered in conjunction with the accompanying drawings wherein.

Figure 1 is a side elevation of a portion of the elevator showing my scraper installed.

Figure 2 is a cross section on the line 2—2 of Fig. 1.

Figure 3 is a cross section on the line 3—3 of Fig. 1.

Figure 4 is a fragmentary side elevation of a modified form of scraper.

Figure 5 is a cross section on the line 5—5 of Figure 4.

There is illustrated a pair of sills 10, which have bearings 11 for support of a roller 12 about which the grader belt 13 travels during operation, this being a well known and conventional construction.

Upon the upper edge of the sills 10 in advance of the roller 12 there is mounted a scraper blade 14, and as clearly shown in Figure 1, the blade comprises a sharpened edge 15 adapted to contact the peripheral edge of the roller.

The blade 14 is obviously of a length greater than the roller and includes longitudinally extended foot members 16 adapted to lie flush upon the sills. The foot members 16 each have longitudinal slots 17 and receive a bolt 18. It will thus be seen that the scraper may be adjusted toward or away from peripheral contact with the roller.

The scraper 14 includes a plurality of deflector vanes 19 suitably spaced longitudinally of the scraper, these vanes diverging in opposite directions from the medial line of travel of the belt, as may be seen in Figure 3. The deflector vanes

19 are each arcuately shaped at their forward ends, as at 20, so as to fit the contour of the roller 12, and of a height so as to stop short of the underside of the upper reach of the belt 13.

The vanes 19 are slightly canted and extend obliquely to the longitudinal edges of the belt so that material loosened from the roller and belt will be caused to discharge over respective sides of the belt. Any number of deflectors may be employed, this depending upon the width of the belt.

In use, material which may adhere to the roller 12 will be scraped therefrom by virtue of the blade 14, and similarly material upon the under side of the upper reach of the belt 13 will be removed due to contact with the deflectors 19. As has been stated, the loosened material will then be conducted by means of the deflector vanes to respective sides of the belt and discharged over the edges thereof. This removal of the loosened material is made possible due to the material striking the deflectors with considerable force causing deflection of the material in the direction of the sides of the belt.

In Figures 4 and 5 a modified form of scraper is shown embodying the sills 10, bearings 11, roller 12 and belt 13, as before described. The sills 10 support a scraper 14', which in this instance, is formed from a sheet strap of metal of suitable gauge and width for the purposes intended. The ends of the strap are of a slightly greater width than the major portion of the strap, and inwardly of the ends the metal is cut as at 21, permitting the bending of the ends to form foot members 22. The foot members are each provided with a longitudinal slot 23 for reception of a fastening bolt 24, the latter being engaged in respective sills 10 for rigid yet adjustable securing of the scraper, as will be apparent.

The scraper 14 is inclined at a suitable angle, the upper portion 25 being slightly curved to present the scraping edge 26 so as to engage the roller 12 at such angle as to readily scrape material therefrom.

Upon the rear face of the scraper 14 there are secured deflector vanes 27 and 28, the vanes 27 functioning to deflect loosened material to one side of the belt, while the vanes 28 act to discharge material to the other side thereof, this being effected by the inclination of the vanes, and impact of material thereagainst, as previously explained.

The vanes 27—28 in the present instance are elongated metal straps, one end of which is provided with an attaching foot 29, bent at an angle

so as to abut flatly against the scraper 14, where they may be welded or otherwise secured. The bend between the foot and the vanes is such as to slightly cant the vanes in a direction to deflect loosened material to respective sides of the belt.

5 While I have shown and described preferred constructions, this is by way of illustration only, and I consider as my own all such modifications in structure as fairly fall within the scope of the 10 appended claims.

I claim:

1. In a scraper for cleaning the belt and lower roller of elevating graders, a frame, a roller revolvably mounted thereon, a belt trained about 15 the roller, a scraper carried by the frame and extending beyond the ends of the roller, said scraper having a plurality of spaced elongated deflector vanes positioned beneath the upper reach of the belt and spaced from the lower reach of the belt,

said deflector vanes being canted and diverging in opposite directions from the medial line of travel of the belt.

2. In a scraper for cleaning the belt and lower roller of elevating graders, a frame, a roller revolvably mounted thereon, a belt trained about the roller, a scraper, said scraper having a slotted foot at its ends, said slot extending longitudinally thereof, a bolt extended through the slot and threadedly engaged in the frame, the scraper extending beyond the ends of the roller, said scraper having a plurality of spaced elongated deflector vanes positioned beneath the upper reach of the belt, and spaced from the lower reach of the belt, 10 said deflector vanes being canted and diverging 15 in opposite directions from the medial line of travel of the belt.

ADOLPH G. ANDERSON.
